(57) **ABSTRACT**

A new *Petunia* plant named 'PEHY0056' particularly distinguished by its medium to large sized, yellow flowers with rose margin, medium early flowering and mounding plant habit

1 Drawing Sheet

1

Latin name of the genus and species of the plant claimed:
Petunia hybrida.

Varietal denomination: 'PEHY0056'.

BACKGROUND OF THE NEW PLANT

The present invention comprises a new *Petunia*, botanically known as *Petunia hybrida*, and hereinafter referred to by the variety name 'PEHY0056'.

'PEHY0056' is a product of a planned breeding program. The new cultivar has medium to large sized, yellow flowers with rose margin, medium early flowering and a mounding plant habit

'PEHY0056' originated from a hybridization made in October 2016 in a controlled breeding environment in Enkhuizen, The Netherlands. The female parent was the proprietary selection 'P0266V'. Compared to 'PEHY0056' it has a more trailing plant habit, is later flowering and has a yellow flower color.

The male parent of 'PEHY0056' was the unpatented proprietary selection 'BB2036-1V', a plant with somewhat smaller flowers, a bit more upright plant habit, and a yellow color with burgundy spots.

The resulting seeds were sown in January 2017. 'PEHY0056' was selected as one flowering plant within the progeny of the stated cross in May 2017 in a controlled environment in Enkhuizen, The Netherlands.

The first act of asexual reproduction of 'PEHY0056' was accomplished when vegetative cuttings were propagated from the initial selection in June 2017 in a controlled environment in Enkhuizen, The Netherlands.

BRIEF SUMMARY OF INVENTION

Horticultural examination of plants grown from cuttings of the plant initiated in June 2017 and continuing thereafter, has demonstrated that the combination of characteristics as

2

herein disclosed for 'PEHY0056' are firmly fixed and are retained through successive generations of asexual reproduction.

'PEHY0056' has not been observed under all possible environmental conditions. The phenotype may vary significantly with variations in environment such as temperature, light intensity, and day length.

A Plant Breeder's Right for this cultivar has not yet been applied for. 'PEHY0056' has not been made publicly available prior to the effective filing date of this application, notwithstanding any disclosure that may have been made less than one year prior to the effective filing date of this application by the inventor or another who obtained 'PEHY0056' directly from the inventor.

The following traits have been repeatedly observed and are determined to be basic characteristics of the new variety. The combination of these characteristics distinguishes this *Petunia* as a new and distinct variety.

BRIEF DESCRIPTION OF THE PHOTOGRAPHS

The accompanying photographic drawings show typical flower and foliage characteristics of 'PEHY0056' with colors being as true as possible with an illustration of this type.

The photographic drawings show in FIG. 1. a flowering plant of the new variety and
in FIG. 2. a close-up of the flowers.

DETAILED BOTANICAL DESCRIPTION

The aforementioned photographs were taken in May 2020 from plants growing indoor in 12 cm pots in Andijk, The Netherlands. These plants were approximately 12 weeks of age.

The plant descriptions and measurements were taken in June 2021 in Andijk, The Netherlands on approximately 12 week old plants that were growing outside in containers.

Color references are made to The Royal Horticultural Society Colour Chart (R.H.S.) 2001.

TABLE 1

DIFFERENCES BETWEEN THE NEW VARIETY 'PEHY0056' AND A SIMILAR VARIETY		
	'PEHY0056'	'Amore Queen of hearts', not patented
Distribution of yellow flower color:	Along mid vein, but not to margin	Along mid vein
Corolla tube color, throat:	Dark bronze throat	Yellow throat
Flower color stability:	Can vary from almost yellow to rose depending on conditions	Rather stable

Plant:

Form, growth and habit.—Mounding plant habit.

Plant height.—13 cm.

Plant height (inflorescence included).—17 cm.

Plant diameter (width).—+/-24 cm.

Roots:

Number of days to initiate and produce roots.—16 days at about 22° C.

Type.—Fine, fibrous, free branching.

Color.—RHS N158D.

Foliage:

Arrangement.—Alternate, simple; sometimes opposite, decussate.

Immature leaf, color upper surface.—RHS 137B.

Immature leaf, color lower surface.—RHS 138B.

Mature leaf, color upper surface.—RHS 137A.

Mature leaf, color lower surface.—RHS 138B.

Length.—5.0-6.0 cm.

Width.—2.5-3.5 cm.

Shape.—Ovate.

Base shape.—Shortly attenuate.

Apex shape.—Acute.

Margin.—Entire.

Texture, upper surface.—Densely covered with short hair.

Lower surface.—Densely covered with short hairs.

Color of veins, upper surface.—RHS 137C.

Color of veins, lower surface.—RHS 137C.

Petiole color.—RHS 137C.

Length.—0.4 cm.

Diameter.—0.3 cm.

Petiole texture.—Densely covered with short hairs.

Stem:

Quantity of main branches per plant.—4-5.

Color of stem.—RHS 137C.

Length of stem.—13 cm.

Diameter.—0.4 cm.

Length of internodes.—1.0-2.0 cm.

Texture.—Dense, mostly glandular short hairs.

Color of pedicel.—RHS 137C.

Length of pedicel.—2.5-3.0 cm.

Diameter of pedicel.—0.2 cm.

Texture of pedicel.—Densely covered with short hairs.

Type.—Flowers solitary in upper leaf axis.

Floret type.—Funnel-shaped; 5 lobed petals; fused at base.

Blooming habit.—Medium to early flowering in green-house, flowering throughout the summer months.

Quantity of inflorescences per plant.—Approximately 25.

Lastingness of individual blooms on the plant.—About 7 days.

Fragrance.—Rather strong smell.

Bud (just when opening):

Color.—RHS N77B at base, RHS 61A at top, RHS 149C in middle.

Length.—4.0 cm.

Width.—1.9 cm.

Shape.—Tridentate.

Immature inflorescence:

Flower horizontal diameter.—5.0 cm.

Color petals, upper surface.—RHS 13A near throat. Margin RHS 61A.

Color petals, lower surface.—RHS 58A at base, RHS 61A at top, RHS 150B in middle.

Mature flower:

Flower horizontal diameter.—6.0 cm.

Flower height (vertical).—5.0 cm.

Color upper surface.—RHS 12A, RHS 13A near throat. Margin RHS 61A.

Color lower surface.—RHS 58A at base, RHS 61A at top, RHS 150C in middle.

Conspicuousness of veins.—Weak.

Apex shape.—Acuminate.

Margin.—Entire.

Waviness of margin.—Weak.

Petal lobation.—Medium.

Petal texture, upper surface.—Smooth.

Petal texture, lower surface.—Smooth.

Corolla tube color outside.—RHS 58A.

Corolla tube color inside.—RHS N170A.

Conspicuousness of veins in tube.—Medium.

Corolla tube length.—2.5 cm.

Corolla tube texture, outside.—Rather dense and short glandular hairs.

Corolla tube texture, inside.—Glabrous.

40 Calyx:

Color of sepal, upper surface.—RHS 137A.

Color of sepal, lower surface.—RHS 137B.

Length.—1.8 cm.

Width.—0.4 cm.

Shape.—Ensiform.

Apex shape.—Acute.

Base.—Fused.

Margins.—Entire.

Texture, upper surface.—Densely covered with short glandular hairs.

Lower surface.—Densely covered with short glandular hairs.

45 Reproductive organs:

Pistil.—1.

Length.—2.4 cm.

Style color.—RHS 142D.

Style length.—1.9 cm.

Sigma color.—RHS 143A.

Stamens.—

Quantity per flower.—5.

Color of filaments.—RHS 157D, RHS 56C near base.

Length filaments.—1.9 cm.

Anther color.—RHS 159A.

Anther length.—0.2 cm.

Anther shape.—Elliptical.

Color of pollen.—RHS 159A.

US PP34,581 P2

5

6

Pollen amount.—Sparse.

Fertility/seed set.—Has not been observed on this hybrid.

Disease/pest resistance.—Has not been observed on this hybrid.

5

What is claimed is:

1. A new and distinct variety of *Petunia* plant named 'PEHY0056' substantially as illustrated and described herein.
